(57) **CLAIM**

The ornamental design for a box, as shown and described.

DESCRIPTION

FIG. 1 is a top perspective view of a box of the present design, shown in its folded, glued, and closed configuration; FIG. 2 is a bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof;

FIG. 9 is a top perspective view of a box of the present design, shown in its folded, glued, and open configuration; FIG. 10 is a bottom perspective view thereof;

FIG. 11 is a right side view thereof;

FIG. 12 is a left side view thereof;

FIG. 13 is a front view thereof;

FIG. 14 is a rear view thereof;

FIG. 15 is a top view thereof;

FIG. 16 is a bottom view thereof;

FIG. 17 is a top perspective view of a box of the present design, shown in its pre-folded configuration;

FIG. 18 is a bottom perspective view thereof;

FIG. 19 is a right side view thereof;

FIG. 20 is a left side view thereof;

FIG. 21 is a front view thereof;

FIG. 22 is a rear view thereof;

FIG. 23 is a top view thereof; and,

FIG. 24 is a bottom view thereof.

The broken lines in the drawings depict fold lines that form no part of the claimed design.
